COLLAPSIBLE INTERLOCKING EXTENSIBLE
TABLE

Alice Duffy, Bronx, N. Y.

Application November 10, 1949, Serial No. 126,473

2 Claims. (Cl. 311—4)

1

This invention relates to tables, and, more particularly, to a collapsible extensible table adapted for use as a card table, a combined bed tray and table, a cutting table, and a myriad of other types of table.

One object of the invention is the provision of a collapsible basic or center table and a plurality of auxiliary extensions therefor, each of said extensions being supported at one end on collapsible legs and at the other end by said center table or another extension.

Another object of the invention is the provision of means for connecting and locking the center table and the various extensions together.

Still another object of the invention is the provision of an extension table connectable with said center table and having collapsible legs adapted to rest on an invalid's bed or on the arm of a convalescent's chair.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the table of the invention, and illustrates the center table with a plurality of extensions connected thereto.

Fig. 2 is a side elevation of the table as used with an invalid's bed or a convalescent's chair.

Fig. 3 is an enlarged view of the underside of the center table, and illustrates the means for latching the extensions thereto.

Fig. 4 is a perspective view of the edge of one of the extension tables and illustrates the means by which it is connected to the center table or to another extension table.

Fig. 5 is a view of the underside of the edge of an extension table, opposite to that shown in Fig. 4, and illustrates the means for latching another extension thereto.

Fig. 6 is a plan view of a trough attachment for said table.

Fig. 7 is an end view of the trough of Fig. 6.

Fig. 8 is a fragmentary view of the leg collapsing means of the table.

Fig. 9 is a fragmentary sectional view on line 9—9 of Fig. 3.

Fig. 10 is a detail perspective view of a latching shutter.

Fig. 11 is a fragmentary sectional view on line 11—11 of Fig. 3.

Fig. 12 is a sectional view on line 12—12 of Fig. 11.

2

Fig. 13 is a sectional view on line 13—13 of Fig. 12.

Fig. 14 is a fragmentary sectional view on line 14—14 of Fig. 1.

Fig. 15 is a fragmentary sectional view on line 15—15 of Fig. 4.

Fig. 16 is a perspective view of a combined ash tray and glass holding attachment for the table.

The basic or center table of the invention comprises a top piece 25 (Fig. 1) from which edging strips 26 extend downward, the legs 27 of the table being located within and pivoted to said edging strips. The legs are pivoted as at 28 (Fig. 8) and each has a headed stud 30 which engages in a slot 31 in a connecting link 32 pivoted to the edging strip 26. Thus the legs 27 can be folded under the top piece 25.

As thus far described the center table is substantially identical with the well-known, so-called card tables, and the various components thereof can be of any material found suitable in these known tables, as for example, wood, metal or plastic.

Two types of extension tables are provided, one that has a pair of legs adapted to rest on the same surface as the center table, and a second that has a pair of legs adapted to rest on the bed of an invalid or on the arm of a convalescent's chair. The former type will be described first.

Each table extension comprises a top piece 33 (Fig. 1) to which are secured peripheral edging strips 34, the two legs 35 of the extension being connected to one of said strips in the same manner as the legs 27 are secured to strips 26. The opposite end of the extension to that at which the legs 35 are located is supported by the center table as at 36 (Fig. 1) or by another extension table as at 37.

The over-bed or chair extensions are identical with those just described except that their legs 39, see Fig. 2, are considerably shorter due to the fact that they rest on a bed or chair arm.

To provide for the support of the legless ends of all said extension tables, the edging strips 26 (Fig. 1) of the center table, and the extension table edging strips 34 to which the legs 35 are pivoted are each provided with a plurality of slots or cutouts 38 which are engaged by hook members 40 (Figs. 4 and 15) which pass through the edging strips 34 at the legless ends of the extension tables and have tails 41 (Fig. 15) secured to the inner faces of said strips.

To engage the hook members 40 in the slots 38 the edge of the extension table is lifted

slightly, the hook member slid into the slot and the table lowered to engage the hook member.

In some instances the arrangement just described for supporting the legless ends of the extension tables is entirely satisfactory, but in other instances means need be provided for locking the hook members 40 in engagement.

To this end the underside of the center table top piece 25 has slidably mounted thereon adjacent each edging strip 26 by means of brackets 42 a long metal bar 43 to which is secured the tails 44 of a plurality of latching shutters 45 (see also Figs. 9 and 10), one normally in alignment with each of the slots 38. Each of the bars 43 is connected by a lever 46 pivoted at 47 to the table top piece 25 with a circular rocking plate 48 journaled on a post 50 (Fig. 13) projecting downward from a bearing plate 51 secured to the bottom face of the top piece 25 by screws 52 (Fig. 12). The end of post 50 is threaded to receive a nut 53 (Figs. 3 and 11) adapted to hold the rocking plate 48 in place on said post. A spring 54 tensions the rocking plate 48 and the connected parts to the positions shown full lines in Fig. 3, further movement of the parts being prevented by the engagement with a bracket 55 mounted on the lower edge of one of the edging strips 26, of the handle 56 of a long control link 57 pivotally connected at its other end to the rocking plate 48.

The construction is such that the spring 54 normally holds all of the shutters 45 in alignment with the slots 38, but said shutters can be moved laterally out of alignment with said slots to permit the hook members 40 being inserted into the slots by pulling on the handle 56 of control link 57. When the shutters are moved out of alignment with the slots, the hook members 40 (see also Fig. 4) are inserted through said slots and spring 54 allowed to move the shutters back to normal position, where they then engage the hook members 40 as shown in Fig. 14, and prevent the latter from being disengaged from the slots 38.

It will be noted that the levers 46 are connected to rocking plate 48 by means of pin and slot and as said plate is rocked, are moved through dead center, the slots sliding on the pins.

A similar latching arrangement to that described above is provided for the slots 38 in the leg end, edging strip 34 of each extension table. This arrangement comprises a shutter 45 for each of the slots 38 (Fig. 5), said shutters having their tails 44 secured to a bar 43 slidably mounted in brackets 42 the same as described above. However, in the present arrangement, one end of the bar 43 is extended through the adjacent edging strip 34 and is provided with a handle 58 which in the normal position of the parts is held in engagement with the outer face of said edging strip by a spring 60 which acts, in the illustrated instance, on the tail 44 of one of the shutters 45.

It is believed obvious that this arrangement operates to secure two extensions together in identically the same manner as that described above in connection with securing an extension to the center table.

According to the invention, any number of extensions of either type can be connected with the center table in any desired combination.

This invention also provides a trough 61 (Figs. 2, 6 and 7) for cigarettes, cards, magazines, etc., which can be removably secured to any of

the edges of the center table or to the slotted edge of any of the extension tables.

The trough 61 may be of any formation, that shown in the drawings having a deep portion 62 for magazines and the like and a shallow portion 63 for smaller articles, said shallow portion being divided up into compartments by partitions 64. One longitudinal wall of the trough 61 is provided with a plurality of hook members 65, one for each of the slots 38 in an edge of the center table or the leg edge of an extension table, said hook members being identical with the hook members 40 described hereinbefore, and being utilized in exactly the same manner as said hook members 40 to secure the trough in place.

According to the invention one or more combined ash tray and glass holder attachments are provided for securement to the corners of the center table. Said attachment comprises (Figs. 1 and 16) a strip 66 of sheet metal or the like bent in the form of a right angle and having a glass holding receptacle 67 secured to each leg thereof and an ash tray 68 secured to the external corner thereof. In order to provide for securing the attachment to the center table, each of the legs of the strip 66 has mounted thereon a hook member 70. The hook members 70 engage the proximate slots 38 of a pair of right angled edging strips 26 and secure the attachment on the corner of the table as shown in Fig. 1. The hook members 70 function in exactly the same way as the hook members 40 described hereinabove.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. The combination of a center table having a top piece, a plurality of edging strips, one extending downward from each of the edges of said top piece and each including a plurality of longitudinally spaced slots, and a table leg adjacent each of the corners of said top piece, with one or more extension tables each having a pair of legs at one end thereof, a top piece, a plurality of edging strips, one extending downward from each of the edges of said top piece, the edging strip adjacent said pair of legs including a plurality of longitudinally spaced slots and the edging strip opposite the slotted one having secured thereto a plurality of hook members one to engage each of the slots associated with one edge of the center table, or the slots in the edging strip of another extension table; and a latching arrangement associated with said center table to secure the extension tables thereto, said arrangement comprising a latching shutter adjacent each of the slots in the center table edging strips, a plurality of bars slidably mounted on the underside of said center table top piece, one to connect all of the latching shutters adjacent each edging strip, a rocking plate, a pivoted lever connecting each of said bars with said rocking plate, a spring to rock said plate and engage said latching shutters with said hook members, and a control link connected to said rocking plate and extending beyond the edge of the table for manual operation to free said shutters from said hook members, and a latching arrangement associated with each of said extension

tables, the latter said arrangement comprising a latching shutter adjacent each slot in the extension table edging strip, a bar slidably mounted on the underside of the extension table top piece, and connecting all of the last said shutters, said bar extending beyond the edge of the table, a spring to engage said latching shutters with said hook members, and a handle on the projecting end of said bar for manual operation of the latter to free said latching shutters from said hook members.

2. The combination of a center table having a top piece, a plurality of edging strips, one extending downward from each of the edges of said top piece and each including a plurality of longitudinally spaced slots, and a table leg adjacent each of the corners of said top piece, with one or more extension tables each having a pair of legs at one end thereof, a top piece, a plurality of edging strips, one extending downward from each of the edges of said top piece, the edging strip adjacent said pair of legs including a plurality of longitudinally spaced slots and the edging strip opposite the slotted one having secured thereto a plurality of hook members one to engage each of the slots associated with one edge of the center table, or the slots in the edging strip of another extension table; a latching arrangement associated with said center table to secure the extension tables thereto, said arrangement comprising a latching

20

shutter adjacent each of the slots in the center table edging strips, automatic means to move said latching shutters into position to engage said hook members, and manual means to move said latching shutters free of said hook members, a latching arrangement associated with each of said extension tables, the latter said arrangement comprising a latching shutter adjacent each slot in the extension table edging strip, a bar slidably mounted on the underside of the extension table top piece and connecting all of the last said latching shutters, said bar extending beyond the edge of the table, a spring to engage said latching shutters with said hook members, and a handle on the projecting end of said bar for manual operation of the latter to free said latching shutters from said hook members.
